VENETIAN BLIND HEAD-BAR SUPPORTING
BRACKET

Harry Nelson, New York, N. Y., assignor to
Lorentzen Hardware Mfg. Corp., New York,
N. Y., a corporation of New York

Application December 5, 1946, Serial No. 714,210

9 Claims. (Cl. 248—264)

1

This invention relates to Venetian blinds and more particularly to a Venetian blind head-bar-supporting bracket.

Venetian blinds designed for mounting in or adjacent to door and window frames are customarily provided with a head bar which is supported on the door or window frame by special supporting brackets, and which serves in turn to support a tilt bar from which the balance of the Venetian blind depends. Head bars for Venetian blinds are often formed of a strip of wood provided with a channel formed in the upper face of the bar to provide a runway for the lift cords.

The supporting brackets for Venetian blinds are usually mounted adjacent to the top of the door or window frame for supporting the blind across the wall opening. These brackets are usually adapted for either "inside" or "outside" mountings of the blind, an "inside" mounting being one in which the blind is nested within the wall opening; and an "outside" mounting being one in which the blind extends across and beyond the wall opening.

The tilt bar of a Venetian blind is supported at its ends from the head bar; and where the tilt bar is more than three or four feet long, it is customary to provide one or more "center" supports to additionally support the tilt bar from the head bar. These "center" supports are customarily located adjacent intermediary ladder tapes which aid in supporting the balance of the blind. The load transmitted to the head bar by the center supports tends to bow the head bar downwardly unless some additional support is given the intermediary portions of the head bar. Accordingly, intermediary brackets are often secured to the door or window frame for supporting the head bar adjacent to the tilt bar center supports. While intermediary head bar brackets are most frequently used in installations where the tilt bar is provided with center supports, such brackets may also be used when the tilt bar is supported only at its ends.

Venetian blind head bars formed of wood are subject to the usual distortion of wood due to its drying out over a period of time. This problem is particularly acute at the present time due to the shortage of properly seasoned wood, so that it is often necessary to form head bars of wood which is of poor quality or improperly seasoned, resulting in head bars which have a tendency to twist and bow both before and after installation of the blind.

An object of the present invention is to provide an intermediary head-bar-supporting bracket

2

of thin gauge metal having the strength and rigidity of a bracket formed of much heavier gauge metal.

Another object of the invention is to provide an intermediary head-bar-supporting bracket in which the surface of the head bar of the blind is prevented from contacting the heads of the bracket installation screws.

A further object of the invention is to provide an intermediary bracket capable of supporting a Venetian blind head bar against distortion.

A further object of the invention is to provide means whereby the head bar of a Venetian blind is better secured in alignment throughout its length.

A still further object of the invention is to provide an intermediary support for Venetian blind head bars which lends itself to inexpensive and rapid manufacture by stamping from sheet metal, and which will be durable and serviceable in operation.

Further objects, and objects relating to details and economies of manufacture, installation and use, will more definitely appear from the detailed description to follow.

My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification.

Fig. 1 of the drawings is a front elevation of a Venetian blind head bar organization, showing the head bar supported by suitable brackets, and showing a tilt bar mounted beneath the head bar.

Fig. 2 is a perspective view showing the intermediary bracket in blanked-out form including screw holes and reinforcing beads.

Fig. 3 is an isometric view of the completed intermediary bracket.

Fig. 4 is a vertical cross section of a head bar and intermediary bracket, taken in general on the line 4—4 of Fig. 1.

Fig. 5 is a cross section similar to Fig. 4 showing the mounting of the intermediary bracket for an "outside" installation of a Venetian blind.

In the form shown, the present invention contemplates the forming of a generally U-shaped intermediary head-bar-supporting bracket from relatively thin sheet metal. Longitudinally-ex-

tending inwardly-projecting beads or corrugations are formed in the metal, these beads serving to reinforce the metal throughout its length and particularly at the points where the metal is transversely bent at the base of the legs of the U-formation.

Holes may be formed in the legs and bottom of the U-formation for mounting the bracket adjacent to a wall opening and for securing a Venetian blind head bar to the bracket. These holes are located between the longitudinal beads so as not to interfere with the reinforcing function of the beads and so that the beads will serve to space the sides of the head bar from the heads of fasteners, such as screws or nails, which secure the bracket in position. By this means, scratching and marring of the surface of the head bar is prevented.

In its preferred form, the sheet metal bracket is of squared U-shape, one leg and the bottom of the U-formation being of the same width and the other leg being somewhat narrower. Inwardly projecting beads are formed in the sheet material to increase the resistance of the metal against bending. These beads are carried around the transverse bends separating the bottom portion from the legs of the U-formation, instead of being interrupted thereby, in order to reinforce the area of the bend. The holes provided in the bracket for mounting screws have cylindrical walls, no chamfer being necessary inasmuch as the inwardly-projecting beads render countersinking of the mounting screws unnecessary. The bracket may be mounted by use of flat-headed or round-headed screws, the beads being of sufficient depth that a head bar when placed within the bracket will contact the beads rather than the screw heads, thus preventing marring and gouging of the head bar.

Fig. 2 shows a blank 10, from which the intermediary bracket 11 may be considered as being formed. This blank is formed from a flat sheet of relatively thin gauge metal, preferably steel. The blank 10 is generally rectangular in outline and of uniform width throughout most of its length, the blank being stepped down at a point 14 to provide an end portion 12 of somewhat reduced width. Marginal beads or corrugations 15, 16 are formed along longitudinal edges of the wider portion 13 of the blank and marginal beads 16, 16 are formed along the longitudinal edge of the narrower portion 12 of the blank, the beads 16, 16 extending considerably beyond the stepped point 14 of the blank. In addition, a central bead 17 extends from the wider end of the blank 10 to considerably beyond the point 14 of the blank. All of the beads are formed on a common side of the blank.

A plurality of spaced holes 19 are formed in the blank 10 in the space between the beads as indicated in Fig. 2 for the reception of fasteners such as screws for mounting the bracket and for securing a Venetian blind head bar to the bracket. The blank 10 may be conveniently fabricated in a known manner between dies actuated by a conventional press.

The bracket having been blanked after the fashion shown in Fig. 2, right angle bends are formed along the lines 20-20 and 21-21 shown in Fig. 2 to form the completed bracket shown in Fig. 3. Bending the blank 10 to the form of the U-shaped bracket 11 shown in Fig. 3 may be accomplished in a press by the use of bending dies, these dies preferably serving to prevent flattening or collapsing of the beads 15, 15, 16, 16

and 17 at their intersection with the bending lines 20-20 and 21-21. By preventing flattening of the beads, the transverse surface at all points along the length of the bracket 11 is non-planar, thus providing a bracket that is much stronger than one having a planar zone. Accordingly, this bracket may be fabricated of much thinner steel than one formed of a planar sheet. The bracket may be plated or painted in any well-known manner to prevent rust. This plating may be performed prior to fabrication of the blank, if desired.

The intermediary bracket above described may be installed in the Venetian blind head bar organization shown in Fig. 1. Fig. 1 discloses a head bar 22 formed of a rectangular strip of wood provided with a longitudinal channel 24 in the top surface thereof as shown in Figs. 4 and 5. Channel 24 accommodates lift cords 25 which serve to operate the blind. A tilt bar 26 is rotatably mounted below and parallel to the head bar 22 by a combined tilt bar bracket and cord lock 27 and a tilt mechanism 29. Fittings 30 and 31 positioned in the ends of the tilt bar 26 serve to engage the tilt bar with the combined tilt bar bracket and cord lock 27 and tilt mechanism 29, respectively. A conventional control cord 32 passed around a cord pulley 34 on the tilt mechanism 29 serves to oscillate the tilt bar 26. This head bar and tilt bar assembly is well-known in the art and need not be described herein in detail.

The head bar 22 is supported at its ends by installation brackets 35, 35, which are of the same construction but of opposite hand. This is a well-known type of bracket shown in my Patent 2,281,043 of April 28, 1942. The bracket has a horizontal flange 37 for engagement with the underside of the head bar 22, one or more holes being provided therein for the reception of screws such as 41 for positively engaging the underside of the head bar 22 with the flange 37. Holes are provided in the vertical web 46 for the reception of screws such as 49 for the "inside" mounting shown in Fig. 1. The bracket is also provided with a rear flange 42 having holes 40 therein to accommodate mounting screws (not shown) for "outside" installation of blinds.

For the "inside" mounting shown in Fig. 1, the intermediary head bar bracket 11 is mounted on the underside 50 of a wall opening. The bracket 11 is secured in position by screws 51 engaged in the holes 19 of the wider leg of the bracket and secured in the underside 50 of the wall opening. The relationship of mounting of the intermediary bracket 11 to the installation brackets 35, 35 is such that the narrow leg 12 of the intermediary bracket and the horizontal flange 37 of each of the installation brackets lie in substantially the same horizontal plane. Accordingly, when the head bar 22 is positioned on the horizontal flanges of the installation brackets 35, 35, the intermediary portion of the bar is supported in horizontal alignment by the bracket 11.

Installation brackets, such as are used to support the ends of a head bar, are normally provided with some means to prevent displacement of the head bar from the horizontal flanges of the bracket. In addition, in some installations the ends of the head bar are restrained against any movement relative to the installation brackets. In the assembly shown in Fig. 1, the ends of the head bar 22 are firmly fixed to the horizontal flange 37 of each installation bracket by means of screws 41 engaged in the head bar. While this

means of securing the head bar to the installation brackets has certain disadvantages, particularly in that the removal of the complete blind from the brackets entails more work, the ends of the head bar are retained in positive alignment, thus tending to restrain the head bar against excessive warpage.

If desired, the head bar may also be secured to the intermediary support. Figs. 1 and 4 disclose the securing of the head bar 22 to the bracket 11 by means of a screw 52 engaged in the underside of the head bar. Firmly securing the head bar to the intermediary bracket has certain advantages in that the head bar is maintained in better alignment and any tendency to warp or twist is restrained. Further, if the head bar is already in warped or twisted condition, the misalignment may often be corrected by so securing the head bar to the intermediary bracket. It is to be understood that this securing of the head bar to the intermediary bracket is of particular utility in combination with installation brackets which firmly position the ends of the head bar.

Fig. 5 of the drawings discloses the mounting of an intermediary bracket on the front face of a door or window frame for a so-called "outside" mounting of a blind. In the "outside" mounting, the screws 51 are positioned in the holes 19 located in the bottom of the U-formation of the bracket 11. Hence, the intermediary bracket herein described can be used interchangeably and without alteration for either an "inside" or "outside" blind mounting.

A not readily apparent advantage of the bracket herein disclosed is that it is unnecessary to provide chamfered holes for the bracket mounting screws 51. The cylindrical walled holes 19 of the bracket 11 are easily formed in the same stamping operation in which the beads of the blank shown in Fig. 2 are formed. To chamfer these holes would require an additional operation. Further, it is not necessary to use any particular type of screws in securing the bracket in position, either round or flat-headed screws being equally satisfactory. These advantages are derived from the inwardly-projecting parallel beads 15, 15 and 17 which maintain the adjacent surfaces of the head bar 22 somewhat spaced from the heads of the mounting screws 51. The ribs provide a smooth bearing for the removal or installation of the head bar so that gouging of the surface of the head bar by the heads of the mounting screws 51 is prevented. In addition, these ribs similarly aid in the removal or installation of a warped or twisted head bar which may be so out of alignment as to bind with considerable pressure against the legs of the bracket 11.

While the ordinary use of the bracket herein described is as an intermediary support for a head bar, there are certain installations such as corner windows in which the usual installation bracket cannot conveniently be used at one end of the head bar. For such installations, the bracket herein described may be used to good advantage, and it is within the scope of this invention to use this bracket for supporting the Venetian blind head bar at any point along its length. Likewise, it is also obvious that two or more brackets of this type may be used at intermediary points along the head bar.

I claim:

1. A supporting bracket for a Venetian blind head bar comprising a rigid relatively light gauge U-shaped sheet metal member having a plurality

5 of inwardly pressed longitudinal corrugations serving to reinforce the bracket and having a plurality of holes located in the bottom and one leg of the U-formation between the corrugations thereof for receiving screws for mounting the bracket.

2. A supporting bracket for a Venetian blind head bar comprising a rigid relatively thin U-shaped sheet metal member having a plurality of inwardly pressed longitudinal corrugations serving to reinforce the bracket, one of the legs of said bracket being of less width than the other leg, and the bracket having a plurality of holes located in the bottom and one leg of the U-formation between the corrugations thereof for receiving screws for mounting the bracket.

3. A rigid supporting bracket for a Venetian blind head bar comprising a thin sheet of metal having a pair of substantially right angle transverse bends forming it into a U-shape and having a plurality of inwardly pressed longitudinal beads serving to reinforce the bracket, said bracket having a plurality of holes located between the beads thereof in one of the legs and in the bottom portion of the U-formation for receiving screws for mounting the bracket.

4. A rigid supporting bracket for a Venetian blind head bar comprising a thin sheet of metal having a pair of substantially right angle transverse bends forming it into a U-shape and having a plurality of inwardly pressed longitudinal beads extending around the transverse bends and serving to reinforce the bracket, said bracket having a plurality of holes located between the beads thereof for receiving screws for mounting the bracket.

5. A rigid supporting bracket for a Venetian blind head bar comprising a thin sheet metal stamping having a pair of substantially right angle transverse bends forming it into a U-shape and having inwardly pressed marginal beads extending around the transverse bends and serving to reinforce the bracket, said bracket having a plurality of holes located between the beads thereof for receiving screws for mounting the bracket.

6. A rigid supporting bracket for a Venetian blind head bar comprising a thin sheet metal stamping having a pair of substantially right angle transverse bends forming it into a U-shape, and having inwardly pressed marginal beads extending around the transverse bends and serving to reinforce the bracket, said bracket having a plurality of holes located between the beads thereof in one of the legs and in the bottom portion of the U-formation for receiving screws for mounting the bracket.

7. A rigid supporting bracket for a Venetian blind head bar comprising a thin sheet metal stamping having a pair of substantially right angle transverse bends forming it into a U-shape, one of the legs of the bracket being of greater width than the other leg thereof, and a plurality of inwardly pressed longitudinal marginal beads extending around the transverse bends and serving to reinforce the bracket, said bracket having a plurality of holes located between the beads thereof for receiving screws for mounting the bracket, certain of the holes being in the wider leg and out of alignment with the narrower leg.

8. A rigid supporting bracket for a Venetian blind head bar, comprising a thin sheet metal stamping having a pair of substantially right angle transverse bends forming it into a U-shape having a base and two legs, the base as well as

one leg and the base end of the other leg being wider than the remainder of the other leg, and marginal beads extending adjacent to the longitudinal edges of the bracket, the marginal beads of the narrower and wider portions of the bracket overlapping each other. 5

9. A rigid supporting bracket for a Venetian blind head bar, comprising a thin sheet metal stamping having a pair of substantially right angle transverse bends forming it into a U-shape 10 having a base and two legs, the base as well as one leg and the base end of the other leg being wider than the remainder of the other leg, marginal beads extending adjacent to the longitudinal edges of the bracket, the marginal beads 15 of the narrower and wider portions of the bracket

10

overlapping each other, and holes for mounting screws formed in the wider leg between the beads thereof and out of alignment with the narrower leg.

15

HARRY NELSON.
